CARBOY CAP CONSTRUCTION

Peter Nelson, San Francisco, Calif., assignor to
Stauffer Chemical Company, a corporation of
California

Application September 5, 1936, Serial No. 99,580

5 Claims. (Cl. 217—56)

This invention relates to improvements in the construction of carboy casings, and, more particularly, to a device for connecting the casing cap to the main carboy casing.

In Patent No. 1,885,534, of November 1, 1932, assigned to the assignee of this application, there is disclosed a successful carboy cap construction in which the cap is mounted by means of a hinged structure upon the top of the carboy casing. This structure represented a successful advance in the art. However, time has proven that the construction there disclosed was subject to objection. The first of these was that the construction did not permit of close packing of the carboys. Since the carboys are ordinarily filled with heavy chemicals, and since the transportation cost of heavy chemicals is a vital factor in their sale, it is apparent that this is a serious objection, because it is to the advantage of the shipper of the chemicals to pack as many as possible into a freight car. Another disadvantage is that the hinge end piece construction utilized as the cap lock depended upon the use of two hinge pins. These pins sometimes split the wooden end piece or became bent so that the end piece did not hinge well and the cap could not be readily secured.

It is in general the object of the present invention to improve upon carboy casings, particularly the cap construction thereof, to the end that the casing may be repeatedly used.

Another object of the present invention is to improve carboy casing cap mountings to the end that while a removable carboy casing cap is provided, adequate means are available for securing the cap in position so that the protection of the cap for the carboy neck is available.

The invention includes other objects and features of advantage, some of which, together with the foregoing, will appear hereinafter, wherein the present preferred form of construction embodying the invention is disclosed.

In the drawing, Figure 1 is a perspective view of a carboy casing with the cap fitted thereto, and adapted to be secured in place by means of an embodiment of the present invention.

Figure 2 is a plan view of a carboy casing embodying the present invention.

Figures 3 and 4 are respectively figures taken along the lines 3—3 and 4—4 of Figure 2.

Figure 5 is a schematic view illustrating how the carboy casings of the present invention can be readily stacked.

Carboys are usually glass vessels. Because of the comparative fragile nature of these, they are

usually packed in a wooden casing. In the drawing I have indicated a carboy 11 as enclosed in the generally cubical wooden casing 12. The carboy includes a neck 13 which extends beyond the limits of the casing so that contents of the carboy can be readily removed. To provide a top for the carboy casing, in accordance with this invention, wooden strips 14 and 16 are extended across the top of the casing and are secured thereto. These strips are parallel to each other and are secured upon opposite sides of the casing. A like parallel pair of strips 17 and 18 are extended along the other sides of the casing on top of strips 14 and 16. The sets of parallel strips 14—16 are cut out to provide a round opening 20 for the neck 13 of the carboy, the neck continuing beyond the strips.

A cap structure is provided for mounting upon the carboy casing to protect the neck 13. This cap structure, indicated generally by numeral 19, is made up of two members in angular abutment. These members are indicated by numerals 21 and 22, the two members being tied together by side pieces 23 in their angular abutting relationship. The distance between the non-abutting edges of the members 21 rests upon members 14 and 16, while the side pieces 23 rest upon side members 24. It is to be noted that side pieces 23 are spaced from the ends of the angularly positioned members 21 so that the members 24 fit in between the side pieces and the strips 17 and 18. It is also to be noted that members 24 are of the same width as side pieces 23 so that, as appears in Figure 5, carboys can be stacked immediately between each cap structure. Thus carboy 26 is positioned upon carboys 27 and 28 immediately against the cap structures 19 on both of the bottom carboys.

Means are provided for locking the cap structure in position upon strips 14 and 16. This locking means includes a wooden block 31 secured to strip 16 and having an angular face 32 thereon adapted to receive and abut against the member 22 of the cap structure 19. The block member 31 provides an end closure for one side of the frame formed by strip 17, strip 18 and block 21. An end closure 33 is provided for the other opening in the frame, this end closure including beveled edges 34 slidable between the angular faces 36 formed on strips 17 and 18. Recesses 37 are formed in the angular faces to receive dowel pins 38 carried by the end closure 33, movement of the end closure being limited by the pins 38 sliding in the slots 37. A latch 39 is mounted

upon strip 14 to retain the end closure 33 in that position in which the cap is latched.

In fitting the cap to the casing, the latch 39 is turned to that position in which it appears in Figure 1 and the end closure 33 is slid away from the cap. The cap may then be slid toward the end closure slightly to release it from engagement with the member 31 whereupon the cap may be removed entirely.

10 When it is desired to protect the carboy neck, the end closure 33 is moved toward the side of the carboy casing so that the cap can be readily inserted to abut against end closure 31. The end closure 33 is then slid in to abut the cap, and a latch 39 placed in locking position.

15 The foregoing carboy casing cap and the means for connecting it provides a very simple and effective structure. While I have disclosed the present preferred form of the invention, it is to be understood that various changes therein can be made by those skilled in the art without departing from the spirit of the invention as defined in the appended claims.

I claim:

20 1. In combination, a carboy casing having a top thereon through which projects a carboy neck, a cap for said neck, including two angularly positioned members secured together with an end of each member in angular abutment with an end of the other member, a pair of strips extending across said top to cover said top and along each side of said cap, an end closure secured to said top and abutting one of said cap members and positioned between said strips to cover said top, and another end closure slidable on said top and between said strip members to latch and release said cap and cover said top, said strip members extending over a portion of said slidable closure on opposite sides thereof to a 25 restrict movement of said slidable closure to a sliding movement between said strip members parallel to the plane of said top.

30 2. In combination, a carboy casing, a top thereon having an opening therein for passage of a carboy neck, a cap including two opposite angularly positioned members resting on said top for covering said neck, side members positioned on said top on opposite sides of said cap, another member positioned between said side members and extending over one of said angularly positioned cap members, a closure member slidable between and along said side members in the plane of said side members from a position in which said member extends over the other one of said cap members to a position in which said cap member is free, and a pin extending between an adjacent side of one of said side members and said slidable closure member into a cooperating slot in one of said side members to limit sliding 35 movement of said closure member relative to said side members.

3. In combination, a carboy casing, a top there-

on having an opening therein for passage of a carboy neck, a cap for said neck including two opposite angularly positioned members resting on said top in neck covering position, side members positioned on said top on opposite sides of said cap, another member positioned between said side members and extending over one of said angularly positioned cap members, a closure member slidable between said side members and parallel to the plane of said top and the plane of said side members, said side members extending beyond said cap at least on one side thereof, adjacent extending faces of said side members being angularly formed to retain said slidable closure member, and a pin and slot connection 10 between said closure member and at least one member on said top to limit the length of sliding movement of said closure member on said top.

4. In combination, a carboy casing, a top thereon having an opening therein for passage of a carboy neck, a cap for said neck including two opposite angularly positioned members resting on said top in neck covering position, side members positioned on said top on opposite sides of said cap, another member positioned between said side members and extending over one of said angularly positioned cap members, a closure member slidable between said side members and parallel to the plane of said top and the plane of said side members, said side members extending beyond said cap at least on one side thereof, being beveled toward each other, said slidable member having beveled faces on opposite sides thereof to cooperate with beveled faces on said side members to limit movement of said slidable member to a sliding movement coplanar with said top and parallel thereto, and a pin and slot connection between said closure member and at least one member on said top to limit the length of sliding movement of said closure member on said top.

5. In combination, a carboy casing, a top thereon having an opening therein for passage of a carboy neck, a cap for said neck including two opposite angularly positioned members resting on said top in neck covering position, side members positioned on said top on opposite sides of said cap, another member positioned between said side members and extending over one of said angularly positioned cap members, a closure member slidable between said side members and parallel to the plane of said top and the plane of said side members, said side members extending beyond said cap at least on one side thereof, and a pin extending from opposite sides of said slidable member into a cooperating slot formed in each extending side member to restrict movement of said slidable member to a sliding movement on said top in a plane parallel to that of said top.

PETER NELSON.
